CLAIM

The ornamental design for a display device with a graphical user interface for categorization options, as shown and described.

DESCRIPTION

FIG. 1 is a front view of a display device with a graphical user interface for categorization options; and, FIG. 2 is a second embodiment thereof.

The outermost broken lines showing an electronic device illustrate environmental subject matter, whereas the remaining broken lines showing a display device and elements of the graphical user interface illustrate portions of the article. None of the broken line subject matters form part of the claimed design.
